UNITED STATES PATENT OFFICE.

DAVID PETRI-PALMEDO, OF BRIDGEPORT, CONNECTICUT, ASSIGNOR TO ELECTRIC COMPOSITOR COMPANY, OF NEW YORK, N. Y., A CORPORATION OF NEW JERSEY.

SLUG-EVENER FOR LINE-CASTING MACHINES.

1,108,390.

Specification of Letters Patent. Patented Aug. 25, 1914.

Application filed December 14, 1912. Serial No. 736,728.

To all whom it may concern:

Be it known that I, DAVID PETRI-PALMEDO, a citizen of the United States, residing at Bridgeport, in the county of Fairfield and State of Connecticut, have invented a certain new and useful Improvement in Slug-Eveners for Line-Casting Machines, of which the following is a full, clear, and exact description.

10 In some type line casting machines, when slugs are ejected from the mold and pushed between the trimming knives they are delivered into an inclined chute, down which they slide to the galley. In descending, the slugs acquire velocities such that, when they strike the front wall of the galley, they will rebound more or less. The distance which they rebound varies greatly. Sometimes a slug will rebound enough to cause it to re-enter the chute. In that event the operation of the galley packer is apt to break something; and in that event, the slugs are not deposited in an even smooth column in the galley, but present a ragged and irregular 25 appearance.

The object of the present invention is to cushion the impact of the descending slugs, thereby preventing their rebounding, and to even up the column of slugs in the galley. 30 This is done by permitting each slug as it leaves the chute to strike a yielding (not spring cushioned) impact block, which it carries with it beyond the wall of the galley, and then by restoring this impact piece 35 (whose movement under impact is checked by friction only) to its proper position cause the slug to be alined with the other slugs in the galley.

The invention is shown in the accompanying drawings, and is hereinafter described and definitely pointed out in the claims.

In the drawings, Figure 1 is a front elevation of mechanism embodying this invention and some adjunctive parts of a line casting machine. Fig. 2 is a plan view of the same; and Fig. 3 is a side elevation.

Referring to the parts by reference characters, 77 represents a galley into which the slugs or type bars S are to be delivered and assembled. The floor thereof inclines downward slightly toward the front edge; and along that front edge is an upwardly extended front wall 78.

82 represents an inclined chute into the upper end of which the slugs S are deliv-

ered, so that as they slide down the same and arrive at the bottom thereof they will be resting on their lower edges. The bottom of the chute is arranged to discharge said slugs onto the floor of the galley. So much of the construction as has been described is not my invention.

Directly opposite the delivery end of the chute is an impact block 85 which normally occupies a position such that it forms a part 65 of the front wall of the galley. This impact block is secured to and projects upwardly from a sliding bar 86 which is movable endwise and substantially horizontally in suitable bearings 87 beneath the galley.

In sliding down the chute into the galley the front end of each slug will strike this impact block, and will move the same forward, and will go with it as it moves forward, substantially as indicated by dotted 70 lines in Fig. 3. This impact block is not spring cushioned,—that is to say, its forward movement is not resisted by a spring. A cushioning spring in connection with this impact block would practically defeat the 75 object for which the impact block is provided,—said object being to prevent the rebounding of the slug. The forward movement of the impact block and the rod to which it is attached is opposed and finally 80 terminated by friction only,—or, at least, that is the intention.

After the impact block and slug do come to rest, they are both moved rearward again until the impact block is again alined with 85 the front wall of the galley. Broadly speaking, it is a matter of no consequence what means are provided for so moving this impact block back to the stated position. The means shown, however, are believed to embody certain novel and patentable characteristics and are as follows: A lever 88 is pivoted to a fixture on a substantially vertical pivot and normally occupies a position such that it engages with the front side of a 100 pin 89 which projects down from the sliding bar 86.

This invention, in the form shown, is especially adapted for use as part of a line casting machine wherein the power to move 105 the various parts which are concerned in the slug casting and delivering operation is furnished by a shaft which makes just one revolution whenever it is set in revolution by the operator. The drawing shows this 110

shaft, which is indicated by 4. The shaft carries numerous cams which perform functions connected with the movement of the mold from the ejecting position in which it 5 normally stands to the casting position and then back again. It also carries a cam 17 arranged to engage with an arm 11 fixed to a rock shaft 10. It is from this rock shaft that the power is taken to move the means 10 which eject the slug from the mold and cause its delivery into the upper end of the chute. This cam engages with the arm 11 during the later part of the single revolution of the shaft 4, and thereby rocks this 15 shaft in opposition to a spring 12 which moves it in the opposite direction when the cam will permit. An arm 13 is fixed to and projects down from this rock shaft. A link 14 connects this arm with one arm of a bell 20 crank lever 15. The other arm of the bell crank lever is connected by a link 16 with the lever 88. When therefore the shaft 4 is nearing the end of its single revolution it will rock the rock shaft 10, and thereby, 25 through the described train of mechanism will move the lever 88 forward out of engagement with the downwardly extended pin 89. This lever will occupy this position when the slug is delivered into the upper 30 end of the chute and when it falls down the same into the galley, and strikes and moves the impact piece as described. Thereafter the cam 17 allows the rock shaft 10 to be rocked in the contrary direction by the 35 spring 12, and this, through the described mechanism, causes lever 88 to so swing as to push the impact piece back into the alinement with the front wall of the galley. Of course, the slug is carried with it so that 40 the front end thereof is alined with the front end of the other slugs in the galley. The slug may now be moved along the galley together with other slugs in the galley by a galley packer P of any suitable construction, or by hand, if desired. When the 45 parts are in this position the mechanism comes to rest and leaves them there.

The packer as shown is a plate P which is secured to the upper end of a bent arm 7 50 which is fixed to a rock shaft,—the parts being so constructed and arranged that the plate P comes to rest in a position to the left of the impact block, where it forms the left wall of the galley. As above stated, 55 after the impact block has been restored to its normal position, carrying the slug rearward with it, the galley packer is swung to the right, with the result of moving said slug over against the column of slugs, and 60 then moving the entire column to the right a short distance.

Having described my invention, I claim:

1. In a line casting machine, the combination of an inclined chute, adapted to receive 65 a type slug into its upper end, a galley ar-

ranged to receive slugs discharged from the lower end of said chute, a forwardly movable slide, and an upwardly extended impact block secured to said slide and extending upward into the path of a slug discharged into the galley from said chute—said slide being without any restraint other than friction to forward movement when struck by a slug discharged onto the galley from said chute.

2. In a line casting machine, the combination of an inclined chute adapted to receive into its upper end a type slug, and a galley arranged to receive onto its floor slugs discharged from the lower delivery end of said chute,—said galley having an upwardly extended front wall, with a forwardly slideable impact block arranged opposite the discharge end of said chute and normally occupying a position where it forms a part of the front wall of the galley, and means, which are disengaged from said impact block when the same is struck and moved forward by a slug delivered into the galley from said chute, for moving said impact block rearward to restore it to its normal position.

3. In a line casting machine, the combination of an inclined chute adapted to receive into its upper end a type slug, and a galley arranged to receive onto its floor slugs discharged from the lower delivery end of said chute,—said galley having an upwardly extended front wall, with an unrestrained forwardly movable slide having an upward projecting impact block fixed thereto and normally occupying a position in front of the delivery end of the chute and in alinement with the front wall of the galley, a device which normally holds said impact block in the normal position stated, means for moving said device forward to free the impact block from restraint, and means for moving said device rearward to restore said impact block to its normal position after it has been displaced by the impact from a slug discharged into the galley from said chute.

4. In a line casting machine, the combination of an inclined chute adapted to receive into its upper end a type slug, and a galley arranged to receive onto its floor slugs discharged from the lower delivery end of said chute,—said galley having an upwardly extended front wall, with an unrestrained forwardly movable slide having an upward projecting impact block fixed thereto and normally occupying a position in front of the delivery end of the chute and in alinement with the front wall of the galley, a 115 downwardly projecting shoulder on said slide, a swinging arm projecting in front of said shoulder, means by which to move said arm forward to free said slide from restraint, and means to swing said arm rear- 120 125 130

ward, whereby it will, by engaging the shoulder on said slide restore the impact block to its normal position.

5. In a line casting machine, the combination of an inclined chute adapted to receive into its upper end a type slug, and a galley arranged to receive onto its floor slugs discharged from the lower delivery end of said chute,—said galley having an upwardly extended front wall, with an unrestrained forwardly movable slide having an upward projecting impact block fixed thereto and normally occupying a position in front of the delivery end of the chute and in alignment with the front wall of the galley, a 10 downwardly projecting shoulder on said

slide, a swinging arm projecting in front of said shoulder, a rotatable shaft carrying a cam, means operated by said cam for swinging said arm forward to free said slide from restraint so as to leave it free to move unrestrainedly forward when struck by a slug delivered onto the floor of the galley from said chute, and for subsequently swinging said arm rearward to restore said impact 15 block to its normal position.

In testimony whereof, I hereunto affix my signature in the presence of two witnesses.

DAVID PETRI-PALMEDO.
